(57) **CLAIM**

The ornamental design of a handle for a continuous flow drywall finishing tool, as shown and described.

DESCRIPTION

FIG. 1 is a right side perspective view of our handle for a continuous flow drywall finishing tool according to our new design;

FIG. 2 is a first end elevational view of the handle for a continuous flow drywall finishing tool with two bores therein extending the length thereof according to our new design;

FIG. 3 is a second end elevational view of the handle for a continuous flow drywall finishing tool according to our new design;

FIG. 4 is a left side elevational view of the handle for a continuous flow drywall finishing tool according to our new design;

FIG. 5 is a right side elevational view of the handle for a continuous flow drywall finishing tool according to our new design;

FIG. 6 is a top plan view of the handle for a continuous flow drywall finishing tool according to our new design;

FIG. 7 is a bottom plan view of the handle for a continuous flow drywall finishing tool according to our new design; and,

FIG. 8 is a sectional view of the handle for a continuous flow drywall finishing tool according to our new design, taken along lines 8-8 of FIG. 3.

The handle is broken near the center to indicate indeterminate length.
